UNITED STATES PATENT OFFICE.

LEON F. HOFFMAN, OF FRANKLIN, PENNSYLVANIA, ASSIGNOR TO CHICAGO PNEUMATIC TOOL COMPANY, OF NEW YORK, N. Y., A CORPORATION OF NEW JERSEY.

CONTROL DEVICE FOR COMPRESSOR ENGINES.

Application filed June 24, 1924. Serial No. 722,180.

This invention relates to automatic control systems for compressors and their driving engines and more particularly to fluid pressure operated throttles for the latter.

5 One object of the invention is to provide a simple, efficient throttle control device which can be easily and quickly installed on the engine to be controlled. Another object is to form such a device as a unit to be inserted in the fuel or motive agent supply conduit of the engine. Other objects will be apparent from the detailed description of the invention which follows.

In order to illustrate the invention and 15 the manner of its use, one concrete embodiment is shown in the accompanying drawings, in which:

Fig. 1 is a diagrammatical view partly in section disclosing a typical installation of 20 the invention with the operative parts associated therewith;

Fig. 2 is a rear elevational view of the 25 throttle block shown in Fig. 1 partly in section on the line 2—2 of Fig. 3, the pneumatic device having been operated to move the throttle valve to throttling position; and

Fig. 3 is a sectional view substantially on the broken line 3—3 of Fig. 2.

The pneumatic throttle device comprising 30 the present invention is disclosed in Fig. 1 in a typical compressor installation wherein the driving engine A of the compressor fragmentarily disclosed at B is throttled coordinate with the unloading of the compressor. The compressor may be unloaded 35 by any suitable fluid pressure apparatus such as an unloader or pilot valve C connected to receiver pressure by pipe c and discharging pressure fluid when the receiver pressure reaches a predetermined degree 40 through a pipe c' to actuate an unloading valve D and through a branch connection c' to operate the pneumatic throttle device presently to be described. The unloader 45 valve shown is of the type disclosed in U. S. Patent No. 1,224,272 issued May 1, 1917 to W. H. Callan et al. and the unloading valve is of the type disclosed in U. S. Patent No. 1,275,843 issued August 13, 1918 to W. H. Callan, but any suitable or desired apparatus adapted to function in the manner described may be used.

The throttle device comprises a block or 55 casing 4 having a bore or passage 5 therethrough and provided at its extremities with

flanges 6 arranged to register with and to be secured to similar flanges on the carburetor E and intake manifold F respectively of the internal combustion engine A, the device thus being interposed as a unit 60 between the said portions of the engine structure and forming a part of the motive agent supply conduit to the engine. Mounted within the central bore or motive agent passage 5 of block 4 is a suitable 65 throttle valve which may take the form of the ordinary butterfly valve 7 secured to a shaft 8 journalled in bearings in the sides of the block and normally maintained in the open position shown in Fig. 1 by a coiled 70 spring 9 having one end 10 anchored in a recess in the block and the other end 11 engaging a lever arm 12 which is formed with a collar 13 fitting the projecting end of shaft 8 and keyed thereto by a pin 14. 75

On the rear of block 4 and preferably integral therewith is a cylinder 15 into the outer open end of which pipe c' from unloader valve C is suitably connected. A piston 16 is disposed within cylinder 15 for 80 sliding movement and is provided with a stem 17 extending therebeyond to engage the lever arm 12 on shaft 8 so that when the unloader valve C is actuated, fluid pressure 85 discharged by the latter into pipe c' forces piston 16 outwardly to move lever 12 to the position shown in Fig. 2, which movement rotates throttle valve 7 within passage 5 to throttling position indicated in dotted outline in Fig. 2. The throttling position of 90 valve 7 is readily adjusted by means of a stop in the form of a screw bolt 18 provided with a lock nut 19. Bolt 18 screws into an opening 20 in a guard plate 21 which arches over the externally projecting end of shaft 8 and is preferably, though not necessarily, formed integral with the block 4 and the cylinder 15. In the operation of the device, the motive fluid which is released by unloader valve C to act upon the piston 16 is relieved by the unloader valve when the required pressure falls below the predetermined amount and the throttle valve 7 and piston 16 are restored to their normally open and retracted positions, respectively, through 95 the action of spring 9.

From the above it will be apparent that the throttle device herein disclosed provides means for readily adapting the internal combustion engine of an engine driven com- 100

pressor to automatic control coordinate with and responsive to the unloading of a compressor, that the installation of the device as a unit is quickly effected since it requires no changes in the engine itself nor in the engine's equipment, that the device is self contained and is readily adjusted to proper idling position for the engine without any change in the carburetor adjustment, that the throttle device assures positive automatic control of the engine, and that the throttle block can be easily and cheaply manufactured and assembled.

While but a single preferred form of the invention has been herein shown and described, it is to be understood that the invention covers and is intended to cover all changes, modifications and adaptations within the scope of the appended claims.

20 I claim as my invention:

1. A throttle device for internal combustion engines comprising a block arranged to be interposed between the carburetor and the intake manifold of the engine, said block having a bore therethrough arranged to form a part of the intake passage, a throttle valve in said bore having an operating shaft projecting outside said block, a torsion spring on the projecting portion of said shaft yieldingly to hold said valve in open position, an arm on said shaft, an adjustable stop in the path of movement of said arm, means at least partly enclosing said projecting shaft and said arm and sup-

porting said stop, a cylinder in line with said stop, and a piston reciproably arranged within said cylinder and having a projecting stem arranged to engage said arm to move said valve toward closed position on admission of fluid pressure to said cylinder sufficient to overcome said spring.

2. A throttle device for controlling the driving engine of a compressor comprising a block arranged to be interposed between the carburetor and the intake manifold of the engine, said block having a bore therethrough to form a part of the intake passage, a throttle valve in said bore having an operating shaft projecting outside said block, a torsion spring on the projecting portion of said shaft yieldingly to hold said valve in open position, an arm on said shaft, an adjustable stop in the path of movement of said arm, a guard plate integral with said block extending over and partly enclosing the projecting portion of said shaft and said spring, said plate forming a support for said adjustable stop, and means for actuating said valve under control of the fluid pressure produced by the compressor comprising a cylinder integral with said block and said plate, and a piston reciproable within said cylinder and having a stem to engage said arm.

Signed by me at Franklin, Pennsylvania, 65 this 16th day of June, 1924.

LEON F. HOFFMAN.
